A. ROBERT.
AUTOMATIC DISTRIBUTOR OF LIQUID SOAP.
APPLICATION FILED AUG. 13, 1921.
1,408,921. Patented Mar. 7, 1922.

Inventor
Andre' Robert,
By Marsh Clark
Atty's.

UNITED STATES PATENT OFFICE.

ANDRÉ ROBERT, OF LA CHAUX DE FONDS, SWITZERLAND.

AUTOMATIC DISTRIBUTOR OF LIQUID SOAP.

1,408,921.

Specification of Letters Patent.

Patented Mar. 7, 1922.

Application filed August 13, 1921. Serial No. 492,152.

To all whom it may concern:

Be it known that I, ANDRÉ ROBERT, druggist, a citizen of the Republic of Switzerland, residing at La Chaux de Fonds, have 5 invented certain new and useful Improvements in Automatic Distributors of Liquid Soap, (for which I have filed applications in Switzerland May 14th, 1918, Patent No. 78,773; France July 12, 1921; Germany 10 July 11, 1921; Great Britain July 20, 1921, and Italy July 12, 1921,) of which the following is a specification.

Liquid soap distributors are already known, comprising a reservoir whose only 15 orifice discharges into a receptacle containing a definite quantity of soap.

The said quantity of soap obstructs the orifice of the distributor so that no further soap flows into the receptacle until after the 20 quantity of soap therein has been sensibly diminished.

A great disadvantage inherent to distributors of this kind lies in the fact that they allow excessive waste of soap, the economic 25 advantages resulting from the use of liquid soap being thus illusive, for example, in refectories or in public buildings where the consumer has no interest to use soap with economy.

The improved automatic distributor forming the subject of my invention provides, as compared with similar apparatus, very important improvements. The position of the receptacle with regard to that of the 35 reservoir is such that the allowance of soap in the former may be reached only with the finger tips. Further, a rim is provided near the edge of the receptacle adjacent to the consumer, in order to prevent drops of liquid 40 sticking to the fingers. This rim will, preferably consist of two inclined parts with an opening between them, so that any liquid which may accidentally fall between the inclined rim and the edge of the receptacle 45 will flow back and rejoin the allowance of soap contained in the receptacle.

The annexed drawings represent, as a descriptive but not restrictive example, a form of automatic soap distributor according to 50 my invention.

In Fig. 1 the distributor is shown in sectional elevation;

In Fig. 2, it is shown in plan.

The reservoir or tank *a* is provided with a 55 single orifice *b*, a receptacle *c* being pivotally attached to the said tank. The latter may

be attached to the wall by means of a hook *e*. When the tank is in the position represented in Fig. 1, a small quantity of soap first flows into the receptacle; as soon as the bottom of the receptacle is full of soap, the orifice of the tank is obstructed by the latter, so that no more soap may flow. The neck of the tank is very short and it rests against the receptacle, so that the free space between the bottom of the tank and the bottom of the receptacle is just sufficient to permit the allowance of soap to be reached with the finger-tips. This space is moreover narrowed by the rim *f* consisting of two parts, as shown in Fig. 2, slightly inclined to one another, a free space being provided between the two parts of the said rim. This rim prevents drops of soap from adhering to the fingers of the consumer and being carried away by the latter. It results from the above improvements that the use of a distributor according to the invention is particularly well adapted to effect the economy required of apparatus of this kind.

I claim:

1. An automatic distributor of liquid soap consisting of a reservoir provided with a single orifice through which the soap flows, and receptacle into which the soap is deposited and in which the consumer dips his fingers, the orifice being obstructed by the soap contained in the receptacle, characterized by the fact that the relative position of the reservoir and of the receptacle is such that the allowance of soap in the latter may be reached only with the finger-tips.

2. An automatic distributor of liquid soap consisting of a reservoir provided with a single orifice through which the soap flows, and receptacle into which the soap is deposited and in which the consumer dips his fingers, the orifice being obstructed by the soap contained in the receptacle, characterized by the fact that the relative position of the reservoir and of the receptacle is such that the allowance of soap in the latter may be reached only with the finger-tips, the receptacle being provided with a rim against which the fingers press, in order to prevent drops of liquid from adhering to the fingers.

3. An automatic distributor of liquid soap consisting of a reservoir provided with a single orifice through which the soap flows, and receptacle into which the soap is deposited and in which the consumer dips his fingers, the orifice being obstructed by the

soap contained in the receptacle, characterized by the fact that the relative position of the reservoir and of the receptacle is such that the allowance of soap in the latter may 5 be reached only with the finger-tips, the receptacle being provided with a rim against which the fingers press, in order to prevent drops of liquid from adhering to the fingers, said rim consisting of two parts inclined

with respect to one another, a free space being provided between said parts, so that liquid soap which may accidentally fall between the inclined rim and the edge of the receptacle may flow back again into the allowance of soap in the latter. 10 15

In testimony whereof I affix my signature.

ANDRÉ ROBERT.
